UNITED STATES PATENT OFFICE.

JAMES W. WILLIAMS, OF STANLEY, MISSOURI.

CHURN.

No. 867,179.

Specification of Letters Patent.

Patented Sept. 24, 1907.

Application filed April 6, 1907. Serial No. 366,774.

To all whom it may concern:

Be it known that I, JAMES W. WILLIAMS, a citizen of the United States, residing at Stanley, in the county of Pemiscot and State of Missouri, have invented a new 5 and useful Churn, of which the following is a specification.

This invention relates to churns and has for its object to provide a comparatively simple and inexpensive device of this character by means of which the operation 10 of churning may be accomplished with greater facility and less labor than heretofore.

A further object of the invention is to provide a supporting frame having a slide mounted for vertical movement thereon and provided with alined recesses 15 for the reception of the adjacent end of the dasher rod, said slide being operatively connected with and driven by suitable gearing so that by rotating the operating handle a reciprocating movement may be imparted to the dasher.

20 A further object is to provide improved means for securing the crank wheel or disk in position on the driving shaft, and means for preventing accidental displacement of the dasher rod.

A still further object of the invention is to generally 25 improve this class of devices so as to increase their utility, durability and efficiency.

Further objects and advantages will appear in the following description, it being understood that various changes in form, proportions and minor details of construction 30 may be resorted to within the scope of the appended claims.

In the accompanying drawings forming a part of this specification: Figure 1 is a front elevation partly in section of a churn operating mechanism constructed in accordance with my invention. Fig. 2 is a vertical sectional view taken on the line 2—2 of Fig. 1. Fig. 3 is a transverse sectional view taken on the line 3—3 of Fig. 1. Fig. 4 is a transverse sectional view taken on the line 4—4 of Fig. 2. Fig. 5 is a perspective view of a 40 portion of the dasher rod and the adjacent edge of the sliding frame.

Similar numerals of reference indicate corresponding parts in all of the figures of the drawings.

The improved churn forming the subject matter of 45 the present invention consists of a supporting frame including spaced uprights or standards 5 connected at their upper ends by a cross bar 6 which constitutes the top of the frame, as shown.

Secured to the inner faces of the uprights 5 are vertical guides 7 between which is mounted for reciprocation 50 a vertically movable slide or dasher supporting frame indicated as a whole at 8.

The slide or frame 8 consists of transverse bars 9 and

10 connected by vertical bars 11 preferably spaced inwardly from the adjacent ends of the transverse bars 9 55 and 10 so as to accommodate the vertical guides 7, said transverse bars being provided with vertical alined recesses 12 for the reception of the guides 7, as shown.

Spaced laterally from the rear wall 13 of the supporting frame is an auxiliary wall 14 defining an intermediate 60 chamber 15 and journaled in suitable openings in the walls 14 and 15 is a driving shaft 16 provided with a pinion 17 which meshes with a master gear 18 carried by the stub shaft 19 also journaled in the walls 13 and 14. 65

The driving shaft 16 projects laterally beyond the auxiliary wall 14 and is provided with a squared terminal 20 adapted to receive a crank wheel or disk 21, the latter being pivotally connected through the medium of a pitman 22 with the lower transverse bar or 70 cross head 10 of the slide 8.

As a means for locking the disk in position on the squared terminal of the operating shaft 16 there is provided a washer 23 having its central portion seated in correspondingly shaped recesses 24 formed in the face 75 of the crank disk or wheel 21 and provided with a laterally extending arm or spur 25 which is driven or otherwise embedded in the face of the disk, as shown. The disk is further locked against accidental displacement on the operating shaft 16 by means of a locking pin 26 80 which extends through an opening in the squared terminal of the shaft 16 and bears against the adjacent face of the washer 23.

One end of the locking pin 26 is embedded in the adjacent wall of the recess 24 while its opposite end extends through the disk and terminates flush with the periphery of the disk, as shown, there being a recess or depression 27 formed in the periphery of said disk so that the end of the rod or pin 26 may be conveniently grasped with the fingers when it is desired to release 90 the pin preparatory to removing the crank wheel or disk for any purpose. 85

The upper transverse bar 9 of the slide or frame is provided with an opening 29 adapted to receive the reduced end of the dasher rod 30, said rod being provided with transverse notches or recesses 31 adapted to engage the adjacent walls of an opening formed in the front longitudinal edge of the transverse bar or cross head 10 thereby to support the rod in alinement with the churn body. 100

The dasher proper may be of any approved form or construction and in the present instance is shown consisting of a plurality of radiating arms 34 having their terminals inclined or beveled and operating within a churn body 35 of any approved construction. 105

The slide or frame 8 is preferably reinforced and

strengthened by the provision of a back plate 36 having its upper edge recessed at 37 to conform to the contour of the periphery of the disk 21 so that the slide is free to reciprocate upon the supporting frame without coming in contact with the crank disk.

The churn may be operated by power, hand or in any other suitable manner but it is preferred to provide a hand crank 38 which in the present instance is secured to the end of the stub shaft at 9 so that by rotating 10 the crank 38 movement will be imparted to the gearing and through the medium of the crank wheel or disk and slide frame impart a reciprocating movement to the dasher.

From the foregoing description it will be seen that 15 there is provided an extremely simple, inexpensive and efficient device admirably adapted for the attainment of the ends in view.

Having thus described the invention what is claimed is:

A churn including a supporting frame, a slide mounted 20 for vertical movement on said frame, a dasher rod carried by the slide, a driving shaft, a crank wheel secured to one end of the driving shaft and having a recess formed in the face thereof, there being a depression formed in the peripheral edge of the crank wheel, a washer seated in said recess 25 and provided with a lateral spur embedded in the face of the wheel, a locking pin piercing the crank wheel and having one end thereof seated in the peripheral depression of the wheel and its opposite end engaging the driving shaft, a pitman forming a pivotal connection between the 30 driving wheel and slide, and means for rotating the shaft.

In testimony that I claim the foregoing as my own, I have hereto affixed my signature in the presence of two witnesses.

JAMES W. WILLIAMS.
